UNITED STATES PATENT OFFICE.

CARL ALBERT HIRTH, OF CANNSTATT, STUTTGART, GERMANY.

BALL-GRINDING MACHINE.

967,918.

Specification of Letters Patent. Patented Aug. 23, 1910.

Application filed January 27, 1909. Serial No. 474,477.

To all whom it may concern:

Be it known that I, CARL ALBERT HIRTH, a subject of the Emperor of Germany, residing at Cannstatt, Stuttgart, Germany, 5 have invented new and useful Improvements in or Relating to Ball-Grinding Machines, of which the following is a specification.

The invention relates to ball grinding machines, in which one or both of a pair of 10 grinding disks are provided with grooves in which the balls roll, and in which machines the balls, owing to a gap in the track in which they move, are alternatively discharged from and returned to the machine, 15 so that, as the result of continued mixing, the balls are ground in different serial order and in different grooves. This method of working insures the greatest possible degree of uniformity in the diameter and superficial character of the balls. According to 20 the present invention it becomes possible to increase the speed of the grinding disks as desired, with the result that not only is the pressure exerted by the disks smaller, though 25 the efficiency is increased, but also the number of balls that can be ground during a working shift can be increased, so that a much larger number of balls of uniform size can be turned out per shift than formerly. 30 The accuracy of the grinding has also been improved, because not only are the balls sent forward for fresh treatment more rapidly, but they are only ground to a very small extent during each passage through 35 the machine. The increase in the number of revolutions of the disks is rendered possible in accordance with this invention, by the balls being fed into the tracks between the disks, separately, and with such an accelerated 40 speed that they can enter the machine in very close and uninterrupted serial order. The accelerated speed of the balls in entering the machine can be effected, for instance, by feeding the balls into the machine in a 45 row, from a height corresponding with the velocity of the grinding disks, from a track held in a given position and which may consist of a channel or one or more tubes. Another method consists in taking hold of 50 the balls by a rapidly moving device, such as a revolving belt, and, as it were, throwing them into the machine.

The accompanying drawings illustrate, diagrammatically, a number of devices for

accomplishing the desired effect according to this invention.

Figure 1 is an elevation, partly in section, of one form of the invention. Fig. 1^a is a horizontal section of Fig. 1. Fig. 2 is a view similar to Fig. 1, showing a modification. 60 Fig. 2^a is a plan partly in section of Fig. 2. Fig. 3 is an elevation partly in section of another modification. Fig. 3^a is a plan view of Fig. 3. Fig. 4 is an elevation of another modification. Fig. 4^a is a plan thereof. Fig. 65 5 is a vertical section of another modification taken on line A—A Fig. 6. Fig. 6 is a section on line B—B Fig. 5. Fig. 7 is a vertical section of another modification. Fig. 8 is a front view of the same, viewed from 70 the right hand side of Fig. 7. Fig. 9 is an elevation partly in section of another modification. Fig. 10 is a plan thereof with the upper portion removed.

In Figs. 1 and 2 it is assumed that the 75 grinding disks of the machine are mounted vertically, whereas in Figs. 3 and 4 they are horizontally disposed. The devices in Figs. 5 to 8 are applicable to vertically or horizontally mounted grinding disks. Figs. 9 80 and 10 show a combination of the devices according to Figs. 2 and 4, the balls being removed from and returned to the ball grinding machine at different points

The balls are ground between the disks *a* 85 and *b*, of which, the disk *a*, is stationary, while the disk *b*, runs loosely on the shaft *c*, of the disk *a*, and is caused to rotate by a driven belt pulley *d*. The balls *e*, are received in grooves, which may be provided in 90 one or each of the grinding disks *a*, *b*. In order to remove the balls and re-introduce them during the working process, the disk *a*, is provided with a gap *f*, in which the discharge channel *g*, and the feed channel *h*, 95 are arranged.

In the modification shown in Figs. 1 and 1^a, the discharge channel *g*, is divided above the feed channel *h*, into two parts *g*¹ and *g*², which conduct the balls, removed from the 100 grooves, into a collector *i*. From the collector *i*, the balls are lifted by a device not shown in the drawing, mixed together, and passed into the feed channel *h*. This feed channel *h*, consists of separate grooves *h*¹, in 105 which the balls are ranged in a row and are conveyed, at accelerated speed, into the grooves of the grinding disks.

In the modification according to Figs. 2 and 2^a, there are no special means adapted for raising and mixing the balls. In this case the balls are led through the discharge channel g^s , onto a downwardly sloping and curved track, on which they mingle together, and thence reach a quick running band or belt k , which carries them onward into the curved channels l , by which they are returned to the grooves of the ball grinding machine.

When the grinding disks a and b , are mounted horizontally, the disk a , containing the gap f , may be arranged either above or below. If it be placed above, it affords, as shown in Figs. 3 and 3^a, the advantage that the feeding of the balls through the feed channel h^s , composed of the grooves h^1 , is facilitated, but, on the other hand, the removal of the balls is rendered more difficult. It is effected by the balls being lifted out of the grooves by the gently upward-sloping channels g^s , and pushed up to the highest point of the channels g^s , whence they roll down an inclined track and escape from the machine. It is necessary that the channels g^s , should slope upward, because the balls have to be conducted away over the shoulders of the grooves of the grinding disk. If the disk a , be underneath (Fig. 4), the removal of the balls from the machine is rendered easier, since as soon as the balls reach the gap f , they drop out of the machine of their own accord. On the other hand, in this case, the feed channel, which again is composed of separate channels h^s , must be bent in order to introduce between the disks a , b , (from below) the balls descending from above.

In the devices shown in Figs. 5 and 6, the balls are led away and returned through pipes, which can be slitted the whole way along, in order to allow the air to escape as the balls move through them.

The pipes through which the balls are led away, form a downwardly sloping system, crossed by an upwardly sloping system of feed pipes. At the crossing point, the pipes are bent in pairs in such a manner as to lie one above another, with sufficient space between one pair and the next to allow of the passage of a pair of similarly arranged pipes of the other system. Thus, the pipes m , of the descending system, bend over the pipes m^1 , of the same system, and the pipes n , of the ascending system over the pipes n^1 , of the same system.

Fig. 7 is a vertical section through a device by which the balls to be ground retain their serial order as in a spiral groove, and Fig. 8 is a front view of the same viewed from the right hand side of Fig. 7. The device operates in such a way that the balls e which roll in concentric grooves, are taken out of the one groove by the pipes or channels o , and immediately returned to the ad-

joining groove, from which after making a single circuit, they are taken out again and fed to the next groove in the same way. From the last groove they pass through a twice bent pipe or channel, p into the first groove again. The pipe p is provided with branches q and r , through which the balls are fed in succession to the machine, or are removed therefrom, these branches, however, being closed while the machine is running. The branch q is preferably arranged above the innermost groove, into which the balls are run in close order when the machine is being filled, until the balls coming into the channel p from the outermost groove, prevent the further admission of balls. In this case the concentric arrangement of the grooves enables a grooved counter disk to be used in place of the plane counter disk of the known ball grinding machines with spiral grooves, thus affording the advantage of a quicker and more uniform grinding of the balls.

Figs. 9 and 10 show a combination of the devices according to Figs. 2 and 4, the balls being removed from and returned to the ball grinding machine at different points. For this purpose the stationary disk a is provided with several gaps, instead of one only, six of these gaps being provided in the example shown. Each gap interrupts one of the tracks traversed by the balls, though several tracks may be adapted to be interrupted by each gap. At the gaps on the stationary disk the balls fall down automatically out of the machine, and can be returned, by means of any convenient raising device, to the charging hopper s of the high level feed device, whence they are distributed into separate pipes t , which return the balls to the machine, through the various gaps in the under disk a . Underneath the charging hopper s a rotary drum u is located, which carries the balls onward and delivers them into the pipes t in close order. The drum u is provided with grooves v each of which appertains to a pipe t . By altering the diameter of the drum at each groove v the number of balls admitted into the pipes t can be altered in accordance with the fact that the pipes issuing into the outer grooves of the ball grinding machine, have to supply a larger number of balls than the pipes issuing into the inner grooves.

What I claim then is:—

1. A ball grinding machine comprising grinding disks between which the balls are ground, the path of the balls being interrupted by gaps through which the balls are taken from and re-introduced into the machine, separated means or channels in which the balls to be delivered to the grooves in the disk or disks may run, and means to accelerate the speed of the gravitational feeding travel of the balls between the times

they are discharged from and re-introduced into the grooves in the grinding disk or disks so that the balls enter said grooves in as close and uninterrupted procession as possible irrespective of the rotatory speed of the disk or disks.

2. A ball grinding machine comprising grinding disks between which the balls are ground, the path of the balls being interrupted by gaps through which the balls are taken from and re-introduced into the machine, means which form channels for the passage of the balls therealong to the grooves in the grinding disk or disks, and mechanism consisting of a revolving device to feed the balls to the feed channels substantially as and for the purpose described.
3. A ball grinding machine comprising

grinding disks between which the balls are ground, the path of the balls being interrupted by gaps through which the balls are taken from and re-introduced into the machine, means which form channels for the passage of the balls therealong to the grooves in the grinding disk or disks, and a mechanical device consisting of an endless traveling belt to feed the balls to the feed channels substantially as and for the purpose described.

In testimony whereof I have signed my name to this specification in the presence of two subscribing witnesses.

CARL ALBERT HIRTH.
